DESIGN FOR A NAIL FILE

Abraham Alexander Crompton, Uttoxeter,
England

Application April 3, 1939, Serial No. 84,000
In Great Britain October 3, 1938

Term of patent 14 years

To all whom it may concern:

Be it known that I, Abraham Alexander Crompton, a subject of the King of Great Britain, Northern Ireland and the Isle of Man, residing at Uttoxeter, in the county of Stafford, England, have invented a new, original, and ornamental Design for a Nail File, of which the following is a specification, reference being made to the accompanying drawing, forming part thereof.

Figure I is a plan view of a nail file, showing my design.

Figure II is an edge view thereof.

Figure III is a perspective view thereof.

I claim:

The ornamental design for a nail file as shown.

ABRAHAM ALEXANDER CROMPTON.
